(57) **CLAIM**

The ornamental design for a handheld spectroscopy device as shown and described.

DESCRIPTION

FIG. 1 is an isometric view of a new design for a handheld spectroscopy device;

FIG. 2 is a front view of the handheld spectroscopy device of FIG. 1;

FIG. 3 is a left side view of the handheld spectroscopy device of FIG. 1;

FIG. 4 is a rear view of the handheld spectroscopy device of FIG. 1;

FIG. 5 is a right side view of the handheld spectroscopy device of FIG. 1;

FIG. 6 is a top plan view of the handheld spectroscopy device of FIG. 1;

FIG. 7 is a bottom plan view of the handheld spectroscopy device of FIG. 1; and,

FIG. 8 is an isometric explanatory view of the handheld spectroscopy device of FIG. 1.

The broken lines in the drawing views are included for the purpose of illustrating portions of the handheld spectroscopy device that form no part of the claimed design.
